UNITED STATES PATENT OFFICE.

LLOYD G. ILIFF, OF KANSAS CITY, MISSOURI.

PLUG-MICROMETER.

1,396,117.

Specification of Letters Patent.

Patented Nov. 8, 1921.

Application filed December 24, 1920. Serial No. 433,049.

To all whom it may concern:

Be it known that I, LLOYD G. ILIFF, a citizen of the United States, residing at Kansas City, in the county of Jackson and State of Missouri, have invented a certain new and useful Improvement in Plug-Micrometers, of which the following is a specification.

My invention relates to improvements in plug micrometers.

10 The object of my invention is to provide a micrometer with which may be accurately measured the diameters of holes too small to admit the ordinary calipers.

15 The novel features of my invention are hereinafter fully described and claimed.

In the accompanying drawing which illustrates the preferred embodiment of my invention,

20 Figure 1 is a central, longitudinal sectional view of my improved plug micrometer.

Fig. 2 is a side elevation of the same.

Fig. 3 is a front end view of the same.

Fig. 4 is a vertical sectional view of the slotted front cap.

25 Fig. 5 is a cross section on the line 5—5 of Fig. 1.

Fig. 6 is a top view of a portion of the measuring plug.

30 Fig. 7 is an enlarged fragmental portion of the longitudinally graduated cylinder.

Similar reference characters designate similar parts in the different views.

1 designates an elongated measuring member comprising, preferably, a plug having a

35 relatively thin flat tapering portion 2, which may be a central longitudinal section of a cone, and which is adapted to have its smaller end inserted into a hole which is to be measured. The plug 1 has a central

40 longitudinal shank 3 of cylindrical form, which has revolvably mounted on it an externally threaded sleeve 4 on which is fitted the inner end of a hollow cylinder 5, the outer end of which is fitted revolvably on the

45 plug 1, said outer end being externally screw threaded and having fitted thereon an internally threaded cap 6, which is held in the position, to which it may be adjusted, by a lock nut 7. The cap 6 in its front end has

50 a slot 8 in which is slidably fitted the flat tapering portion 2 of the plug.

The inner end of the cylinder 5 has a longitudinal, central, slightly tapering, internally and externally threaded extension 9,

55 fitted to the threaded sleeve 4 and having one or more longitudinal slots 10, and having

mounted on it a nut 11 arranged to press the extension 9 against the sleeve 4 to prevent accidental turning of the cylinder 5.

The exterior of the cylinder 5 has a longitudinal row of graduations 12, Figs. 1 and 7, each of which represents one-tenth of an inch in transverse diameter on the tapering portion 2, the thread of the sleeve 5 being fifty to the inch, and the taper of the portion 60 2 being six inches to the foot. Between the graduations 12 are subdivisions 12', Fig. 7, each representing one-hundredth of an inch in transverse diameter on the tapering portion 2.

70 A barrel 13 has one end revolvably fitted on the cylinder 5. The other end of the barrel 13 is closed and has a central hole 14 through which the sleeve 4 extends. Two nuts 15 and 16 are fitted to the sleeve 4 and 75 bear against opposite sides of the closed end of the barrel 13. By adjusting the nuts 15 and 16, the barrel 13 may be adjusted on the sleeve 4. The left end, Fig. 1, of the shank 3 is threaded and has fitted thereon two nuts 80 17 and 18, the latter having a bearing against the nut 15, and the forward end of the sleeve 4 having a bearing against the enlarged portion of the plug 1. Endwise movement of the sleeve 4 on the shank 3 is thus 85 prevented.

The barrel 13 at its right end, Figs. 1 and 2, tapers to a thin edge arranged to coöperate with the graduations 12 and 12'. Said tapering portion 19 is circumferentially divided into numbered graduations 20, ten in number, the spaces between the graduations 20 being subdivided into ten graduations each.

90 The numbered graduations 20 represent each one thousandth, and the subdivisions 95 designated by 21 representing each one ten thousandth of an inch transverse diameter on the tapering portion 2 and double this amount in longitudinal measurement on the 100 tapering portion. The graduations on the tapering portion 19 are arranged to coöperate with a graduation 22 on the cylinder, Fig. 2.

105 In the left end of the shank 3, Fig. 1, is provided a longitudinal, central, threaded hole in which is fitted a screw 23 on which is rotatably mounted a peripherally milled cylinder 24 having at its inner end one or more longitudinal holes in which are respectively mounted helical springs 25 which 110 respectively bear against balls 26, which are

adapted to enter recesses 27 in the adjacent end of the barrel 13. By means of the cylinder 24 together with the spring actuated balls 26, the barrel 13 may be turned, in 5 using the micrometer, without injuring the threaded connection between the cylinder 5 and the sleeve 4, the balls 26 slipping with respect to the barrel 13 when a predetermined resistance to the turning of the barrel 10 occurs.

In the operation of my invention, the conical portion 2 is inserted in the hole to be measured so as to bear at opposite sides against opposite sides of the hole. The barrel 13 is then turned, preferably by means 15 of the milled cylinder 24, so as to turn the sleeve 4, to which the barrel 13 is clamped by means of the nuts 15 and 16, in a direction such that the sleeve 4 will advance the 20 graduated cylinder 5 and cap 6 until the latter bears against the object having the hole to be measured. When the cap 6 bears against said object and the tapering portion 2 is fitted in the hole in said object, the reading 25 on the micrometer is taken in the usual manner.

In the form shown, the graduations 12 cover a longitudinal length representing three lineal inches, this space being subdivided 30 into fifteen numbered graduations 12 which represent one hundred and fifty one hundredths of an inch, or one and a half inches in transverse diameter on the tapering portion 2. This instrument could, therefore, be utilized for measuring diameters up 35 to one and a half inches. With this construction, the threads of the sleeve 4, being fifty to the inch, the longitudinal length of the tapering portion 2 from its point to its 40 widest diameter would be three inches, the same as the distance between the graduations zero and fifteen on the cylinder 5. The thin flat portion 2 of the measuring member 1 being fitted in the elongated slot 8, 45 holds the measuring member from turning in the cap 6. It also affords a means of measuring different diameters of a hole, other than circular, such as an elliptical or 50 rectangular hole, which two functions could not be effected were the tapering portion circular instead of flat in cross section.

I do not limit my invention to the structure shown and described, as many modifications, within the scope of the appended 55 claims, may be made without departing from the spirit of my invention.

What I claim is:—

1. In a micrometer, a member having a tapering measuring end portion, an externally threaded sleeve rotatable on said member and held from longitudinal movement thereon, an elongated member provided with a longitudinal row of graduations and having threaded engagement with said sleeve, 60 and a barrel member movable with said

sleeve and encircling said graduated member and having a circumferentially graduated end portion arranged to coöperate with the said longitudinal graduations, substantially as set forth. 70

2. In a micrometer, a member having a flat relatively thin tapering end portion adapted for insertion into a hole to be measured, an externally threaded sleeve rotatable on said member and bearing at one 75 end against said member, an elongated member provided with a longitudinal row of graduations and having threaded engagement with said sleeve, means for holding the first named member from turning but 80 permitting it to move longitudinally in the graduated member, a barrel member having means for adjustment longitudinally on said sleeve and for being clamped to the sleeve and encircling said graduated member and 85 having a circumferentially graduated end portion arranged to coöperate with said longitudinal graduations, and longitudinally adjustable means on said first named member engaging said holding means adjacent to the other end of said sleeve, substantially as set forth. 90

3. In a micrometer, a measuring plug having a tapering end portion adapted to be extended into and to measure the diameter of a hole, an externally threaded sleeve revolvable on said plug, an elongated member provided with a longitudinal row of graduations and in which the plug is longitudinally slid able, a cap rigidly attached to one end of the graduated member having a slot through which the tapering portion of the plug extends and which holds the plug from turning in the graduated member, and a member movable with said sleeve and arranged to indicate said graduations, substantially as set forth. 95

4. In a micrometer, a measuring plug having a flat relatively thin tapering end portion, an externally threaded sleeve rotatable and said plug, an elongated member provided with a longitudinal row of graduations and having threaded engagement with said sleeve and in which the plug is longitudinally slid able, a cap on one end of said graduated member having a slot in which said tapering portion of the plug is longitudinally slidably fitted, a barrel member encircling the graduated member and having a circumferentially graduated end portion arranged to coöperate with the graduations on the graduated member and movable with said sleeve, and means for holding the sleeve against longitudinal movement on said plug, substantially as set forth. 110

5. In a micrometer, an elongated member having a relatively thin flat tapering end portion, a supporting member having a slot in which said tapering portion is longitudinally slidably fitted, and means coöper- 115 120 125

ating with said supporting member and the first named member by which may be indicated different transverse diameters of said tapering portion, substantially as set forth.

- 5 6. In a micrometer, a plug having a relatively thin flat tapering end portion, an externally threaded sleeve revoluble on said plug, a hollow cylindrical member having threaded connection with said sleeve and
10 in which the plug is longitudinally slidable and having a longitudinal row of peripheral graduations, a member attached to said cylindrical member and provided with a slot through which said tapering portion ex-
15 tends and is longitudinally slidably fitted and a member movable with said sleeve and arranged to indicate said graduations, sub-stantially as set forth.
7. In a micrometer, an elongated measur-
20 ing member having a relatively thin flat tapering end portion, a hollow cylindrical member in which the measuring member is longitudinally movable and having a longitudinal row of graduations representing dif-
25 ferent transverse diameters of said tapering portion, means movable with said measur-

ing member for registering with said graduations, and a member attached to said cylindrical member and having a slot in which said tapering portion is longitudinally slid-
30 ably fitted and through which said tapering portion is adapted to extend, substantially as set forth.

8. In a micrometer, an elongated measuring member having a relatively thin flat taper-
35 ing end portion, a hollow cylindrical mem-ber in which the measuring member is longi-tudinally movable and having a longi-tudinal row of graduations representing respec-tively different transverse diameters of said
40 tapering portion, indicating means movable with said measuring member and coöper-ating with said graduations, and a member having screw thread connection with said graduated member and having a slot
45 through which said tapering portion is adapted to extend and in which it is longi-tudinally slid able, substantially as set forth.

In testimony whereof I have signed my name to this specification.

LLOYD G. ILIFF.
